UNITED STATES PATENT OFFICE

118,454

DESIGN FOR A FUEL PUMP LIGHT GLOBE

Fred L. Roberts, Ferndale, Mich.

Application May 22, 1939, Serial No. 85,124

Term of patent 14 years

To all whom it may concern:

Be it known that I, Fred L. Roberts, a citizen of the United States, residing in the city of Ferndale, county of Oakland, and State of Michigan, have invented a new, original, and ornamental Design for a Fuel Pump Light Globe, of which the following is a specification, reference being had to the accompanying drawing, forming part thereof, in which

Figure 1 is a front view of a fuel pump light globe showing my new design, and

Figure 2 is a side elevation of the globe shown in Figure 1.

I claim:

The ornamental design for a fuel pump light globe, substantially as shown.

FRED L. ROBERTS.
